Primary Examiner — Robert M. Spear*Assistant Examiner* — Marissa J Cash*(74) Attorney, Agent, or Firm* — Fredrikson & Byron,
P.A.(57) **CLAIM**

I claim the ornamental design for an airplane, as shown and described.

DESCRIPTION

FIG. 1 is a front perspective view of an airplane incorporating my new design;

FIG. 2 is a front elevation view thereof;

FIG. 3 is a right side elevation view thereof;

FIG. 4 is a back elevation view thereof;

FIG. 5 is a left side elevation view thereof;

FIG. 6 is top view thereof;

FIG. 7 is a bottom view thereof;

FIG. 8 is another front perspective view thereof, with the wheels tilted; and,

FIG. 9 is further front perspective view thereof, with the wheels tilted in another angle.

1 Claim, 9 Drawing Sheets(56)
